CROSSWINDER WITH AUTOMATIC DRIVE
CONTROL MEANS

Walter Siegenthaler, Erlenbach, Zurich, Switzerland, assignor to Maschinenfabrik Scharer, Erlenbach, Switzerland

Application September 9, 1944, Serial No. 553,415
In Switzerland September 9, 1943

9 Claims. (Cl. 242—43)

1

This invention relates to cross winders with automatic drive control means operating automatically to regulate the velocity of movement of the feeding thread between the winding continually increasing in diameter and the thread guide, for the purpose of obtaining uniformity of thread feed.

The known arrangements for effecting this kind of automatic drive control are provided without exception with driving means that are arranged exteriorly of the gear box and have driving motion imparted thereto from a driving shaft which is provided in common with a plurality of winding machines which are arranged in a row on the same frame. In such arrangements individual attendance of the winding machines is hampered and said driving means are susceptible to contamination whereby their efficiency may become unsatisfactory or even disturbed.

In order to avoid this drawback, according to the present invention a speed control device is arranged in the gear box which transmits driving motion to the winding spindle so as to regulate said motion dependent upon requirements.

By this means, the advantage over the known arrangements referred to above is obtained, at the same time, that the driving motion of the winding machines of a row can be regulated, that is, chosen at will by means of the common driving shaft either through the intermediary of friction discs or a driving belt of flat or wedge shaped cross section.

An embodiment of the present invention is illustrated by way of example only in the accompanying drawing in which

Fig. 1 is an elevational view,

Fig. 2 a corresponding sectional view, and

Fig. 3 shows a cross section of the gear box.

In the drawing only the parts necessary for a proper understanding of the invention are shown.

The numeral 1 refers to the winding spindle which takes its bearings 3 and 4 in the gear box 2 in an inclined position and the lower portion of which supports a winding carrier 5. The winding spindle 1, the driving arrangement of which will be hereinafter explained, transmits driving movement through a bevel wheel drive 6, 7 to an upstanding fluted shaft 8 which is seated in a foot bearing 9 arranged on the bottom of the gear box 2 and projects into a casing 10 within which it protrudes through a bevel wheel 11 which is suspended from a bearing 12 mounted in a casing 10.

The bevel wheel 11 which is in mesh with the fluted spindle 8 for rotation therewith meshes in a bevel wheel 13 which is secured to a hori-

2

zontal shaft 14 which is mounted in two bearings 15, 16. The bearing 15 is situated in the gear casing 10 and the bearing 16 is arranged on an angular bracket 17 which is connected to this casing.

On the shaft 14 the thread guide drum 18 is secured. The gear casing 10 is engaged by one end of a flexible tension member which passes over a guide roller 19 fastened to the gear box 2 and the second end of which carries a weight 20 by effect of which the load constituted by the gear casing 10 and the thread guide drum 18 is overcome and the drum 18 is thus urged in the direction toward the winding carrier 5, that is, against the crosswind A being in progress of formation on said carrier. The gear casing 10 is vertically displaceably guided by means of two rods 21, 22 which lie in one and the same plane and the lower ends of which rest on a common carrier rail 23 while their upper ends support the gear box 2.

On a cross bolt 24 carried by the bracket 17 on the gear casing 10 two rollers 25 are mounted which bear against the guide rods 21, 22 from the front. Two rollers 26 that are arranged on the upper portion of the gear casing 10 bear against the guide rods 21, 22 from behind by which means the casing 10 is given vertical guidance and is laterally steadied. A spur gear 27 forms with the bevel wheel 13 being housed in the gear casing 10 a self-contained unit. The gear 27 transmits its rotational movement via a screw gear 29 to a thread guide 30 which is arranged on the mounting shaft of said gear outside of the casing 10. This thread guide conducts the winding thread arriving from a lower spool toward the drum 18 which receives the thread by means of its intercrossing groove portions 28.

In the operation of the crosswinder precedingly described the driven winding spindle 1 positively transmits driving motion via the bevel wheel drive 6, 7 to the fluted spindle 8, the bevel gear drive 11, 13 and to the shaft 14 of the thread guide drum 18. Due to the fact that the thread guide drum 18 is urged against the crosswind A in progress of formation on the winding carrier 5 by influence of the weight 20 the thread guide drum 18 is readjusted together with its driving and mounting shaft 14 in accordance with the increase in thickness of the thread winding and is thus moved downwardly, this downward movement being shared by the gear casing 10 so that the bevel wheel 11 is accordingly shifted longitudinally of the spindle 8 in engagement with the spindle fluting.

The thread guide drum 18 exerts on the thread winding A in progress of formation a slight pressure only so that the winding does not become unduly tight but tight enough for preventing the structure of the thread winding from being detrimentally affected by influence of centrifugal force. On the other hand the bearing engagement between the thread guide drum 18 and the thread winding A contributes toward enhancing the precision with which the winding thread is placed on the winding support 5. Again, by virtue of the thread guide drum 18 sharing in the driving movement the winding thread is preserved insofar as it is not subjected to material friction at the point of contact between the drum 18 and the thread winding A. The provision of unidirectional movement at all times during the operation of the machine for the rotating drum which serves as the thread guide facilitates uniformity of tensioning of the winding thread.

Coaxially with the winding spindle 1 is arranged a driving shaft 31 which extends through a twin bearing structure 32, being secured on the gear box 2, and the end of which, projecting out of the gear box 2, is provided with a driving disc 33. The driving shaft 31 carries on its end situated within the gear box 21 a disc 34 which is parallel with a disc 35 secured to the winding spindle 1. Each of the two coupling discs 34 and 35 is provided on its end face confronting the other disc with a circular groove 36 of arcuate cross section. In each of the discs 34, 35 is seated a round control disc 37 which extends transversely of these circular grooves and the centre of which coincides with the common centre point of the two arcuate cross sectional groove portions engaging at a time with the disc 37. The round control disc 37 is mounted by means of a central pin 38 in a mounting stirrup 39 each end of which is mounted on a bolt 40 either of which is arranged on a longitudinal wall of the gear box 2.

One of said bolts provides at the same time a mounting shaft for a spur gear 41 which is carried by an associated neck on the stirrup 39. The spur gear 41 meshes with a spur gear 42 the mounting shaft 43 of which has arranged thereon exteriorly of the gear box 2 a slotted carrier arm 44 into the longitudinally extending guide slot of which engages a cross pin 45 on an adjusting rack rail 46 which is associated with a stop roller 47. In the operation of the crosswinder the driving movement of the driving shaft 31 is transmitted to the winding spindle 1 via the discs 34, 37 and 35 which form together a speed control device.

As precedingly explained the casing 10 lowers commensurate with the increase in thickness of the winding A in progress of formation. In the course of this lowering movement the slotted arm 44 pivots downwardly by action of the rack rail 46 moving together with the casing 10 so that by means of the shaft 43 the two gears 42, 41 are accordingly rotated. In consequence thereof the mounting stirrup 39 is pivotally displaced and the disc 37 of the speed control device is accordingly rocked about the axis provided by the two bolts 40, whereby the speed of revolution of the driving disc 37 and that of the driven disc 35 of the speed control device as well as that of the winding spindle is reduced more and more so as to maintain constant the velocity of winding of the thread on the winding carrier.

The bearing pressure between the thread guide drum 18 and the winding A in progress of formation can be regulated by accordingly choosing a

suitable weight 20. The construction of the machine may also be such that the thread guide drum 18 comes into contact with the thread winding only after the latter has reached a certain thickness.

I claim:

1. In a crosswinder for winding a crosswound thread package, a driven winding spindle for supporting said package for common rotation therewith, a thread guide drum, means for positively driving said drum from said spindle independently of the contact of the guide drum with the thread package in progress of formation on said winding spindle, a drive for said winding spindle, and an automatic speed control device connected between said drive and said positive driving arrangement between said thread guide drum and said driving spindle responsive to the growth of the package for automatically regulating the velocity of the thread winding from said thread guide drum on to said package.

2. In a crosswinder for winding a crosswound thread package, a driven winding spindle for supporting said package for common rotation therewith, a thread guide drum, means for positively driving said drum from said spindle independently of the contact of the guide drum with the thread package in progress of formation on said winding spindle, a drive for said winding spindle, an automatic speed control device connected between said drive and said positive driving arrangement between said thread guide drum and said driving spindle responsive to the growth of the package, and control means included in said speed control device susceptible to the influence of said package increasing in diameter for accordingly automatically regulating the velocity of the thread winding from said thread guide drum on to said package.

3. In a crosswinder for winding a crosswound thread package, a driven winding spindle for supporting said package for common rotation therewith, a thread guide drum, means for positively driving said drum from said spindle independently of the contact of the guide drum with the thread package in progress of formation on said winding spindle, a drive for said winding spindle, an automatic speed control device connected between said drive and said positive driving arrangement between said thread guide drum and said driving spindle responsive to the growth of the package, a pair of parallel coupling discs included in said device between said drive and said winding spindle, and a control disc rockingly arranged on an axis so as to be susceptible to the influence of said package increasing in diameter and operatively interconnecting said coupling discs for reducing the speed of revolution of said winding spindle commensurate with said increasing diameter and accordingly regulating the velocity of the thread winding from said thread guide drum on to said package.

4. In a crosswinder for winding a crosswound thread package, a driven winding spindle for supporting said package for common rotation therewith, a thread guide drum, means for positively driving said drum from said spindle independently of the contact of the guide drum with the thread package in progress of formation on said winding spindle, an automatic speed control device connected between said drive and said positive driving arrangement between said thread guide drum and said driving spindle responsive to the growth of the package, a pair of parallel coupling discs included in said device between

said drive and said winding spindle, each of said discs having on its end face confronting the other disc a circular groove of arcuate cross section, and a control disc rockingly arranged on an axis so as to be susceptible to the influence of said package increasing in diameter and operatively interconnecting said coupling discs by engaging in said grooves in said discs for reducing the speed of revolution of said winding spindle commensurate with said increasing diameter and accordingly regulating the velocity of the thread winding from said thread guide drum on to said package.

5. In a crosswinder for winding a crosswound thread package, a driven winding spindle for supporting said package for common rotation therewith, a thread guide drum, means for positively driving said drum from said spindle independently of the contact of the guide drum with the thread package in progress of formation on said winding spindle, a drive for said winding spindle, an automatic speed control device connected between said drive and said positive driving arrangement between said thread guide drum and said driving spindle responsive to the growth of the package, a pair of parallel coupling discs included in said device between said drive and said winding spindle, a control disc, a mounting stirrup including an axis for said control disc to rock thereabout so as to be susceptible to the influence of said package increasing in diameter and operatively interconnecting said coupling discs, and driving means for adjusting said control disc for reducing the speed of revolution of said winding spindle commensurate with said increasing diameter and accordingly regulating the velocity of the thread winding from said thread guide drum on to said package.

6. In a crosswinder for winding a crosswound thread package, a driven winding spindle for supporting said package for common rotation therewith, a thread guide drum, means for positively driving said drum from said spindle independently of the contact of the guide drum with the thread package in progress of formation on said winding spindle, a drive for said winding spindle, an automatic speed control device connected between said drive and said positive driving arrangement between said thread guide drum and said driving spindle responsive to the growth of the package, a driving coupling disc and a driven coupling disc included in said device in parallel relation to each other between said drive and said winding spindle, and a control disc rockingly arranged on an axis so as to be susceptible to the influence of said package increasing in diameter and operatively interconnecting said coupling discs for reducing the speed of revolution of said winding spindle and that of said drive at the same time commensurate with said increasing diameter and accordingly regulating the velocity of the thread winding from said thread guide drum on to said package.

7. In a crosswinder for winding a crosswound thread package, a driven winding spindle for

supporting said package for common rotation therewith, a thread guide drum, means for positively driving said drum from said spindle independently of the contact of the guide drum with the thread package in progress of formation on said winding spindle, a drive for said winding spindle, an automatic speed control device connected between said drive and said positive driving arrangement between said drum and said driving spindle responsive to the growth of the package for automatically regulating the velocity of the thread winding from said drum and said package as required, and means connected between said winding spindle and said drum, for separating said two parts from each other in accordance with said package increasing in diameter, said separating movement being instrumental in adjusting said control device.

8. In a crosswinder for winding a crosswound thread package, a driven winding spindle for supporting said package for common rotation therewith, a thread guide drum, means for positively driving said drum from said spindle independently of the contact of the guide drum with the thread package in progress of formation on said winding spindle, means for displaceably guiding said drum relative to said winding spindle, an automatic speed control device connected between said drive and said positive driving arrangement between said drum and said winding spindle responsive to the growth of the package, a pair of parallel coupling discs included in said device between said drive and said winding spindle, and a control disc rockingly arranged on an axis so as to be susceptible to the influence of said package increasing in diameter and operatively interconnecting said coupling discs for automatically regulating the velocity of the thread winding from said drum on to said package in accordance with said displacing movement of said drum.

9. In a crosswinder for winding a crosswound thread package, a driven winding spindle for supporting said package for common rotation therewith, a thread guide drum, means for positively driving said drum from said spindle independently of the contact of the guide drum with the thread package in progress of formation on said winding spindle, an automatic speed control device connected between said drive and said positive driving arrangement between said drum and said winding spindle responsive to the growth of the package, a pair of parallel coupling discs included in said device between said drive and said winding spindle, and a control disc rockingly arranged on an axis so as to be susceptible to the influence of said package increasing in diameter and operatively interconnecting said coupling discs for automatically regulating the velocity of the thread winding from said drum on to said package in accordance with the relative displacing movement of said winding spindle.
